ATTORNEY.

UNITED STATES PATENT OFFICE

JOHN B. MILLS, OF DAYTON, OHIO, ASSIGNOR TO OHMER FARE REGISTER COMPANY, OF DAYTON, OHIO, A CORPORATION OF NEW YORK

REGISTERING DEVICE

Application filed September 27, 1924. Serial No. 740,168.

This invention relates to registering devices and more particularly to that type of registering device known as a hub-odometer.

One object of the invention is to provide such a device which will be so constructed as to prevent passage of grease from the hub to the registering mechanism.

Another object of the invention is to provide a registering device of this kind with means whereby an additional dial may be mounted therein, without rearranging or modifying the registering mechanism as a whole.

A further object of the invention is to provide a registering device of this kind which will be simple in construction and easy to assemble and install.

Other objects of the invention will appear as the mechanism is described in detail.

In the accompanying drawings, Fig. 1 is a longitudinal sectional view of a hub-odometer embodying my invention, taken on the line 1—1 of Fig. 2; Fig. 2 is a front elevation of the registering mechanism with the face plate removed; Fig. 3 is a sectional detail view taken on line 3—3 of Fig. 2; and Fig. 4 is a detail view of the actuating device for the driving mechanism.

In these drawings, I have illustrated one embodiment of my invention and have shown the same as applied to a hub-odometer of a well-known construction, but it will be understood that this particular embodiment has been chosen for the purpose of illustration only and that the invention may be applied to registering devices of various kinds and may take various forms without departing from the spirit thereof.

The registering mechanism of the device here shown is mounted in the hub cap 1, which is rigidly secured to the hub of the wheel, not shown, which is rotably mounted upon a fixed spindle or axle 2 and retained in position thereon by a nut 3. The registering mechanism is mounted in a recess 4 at the

outer end of the hub cap and is held against rotation so that it is always in a position in which the registration can be easily read. The hub cap is provided with an opening 5 through which the registration may be read and this opening is preferably closed by a glass or other transparent closure, as shown at 6. Mounted in the recess 4 is a supporting member or plate 7, having arranged on one side thereof and near the periphery thereof a series of studs 8 on which are mounted the registering dials 9 and their actuating mechanism. The actuating mechanism preferably consists of a train of gears 10 and a ratchet wheel 11 connected with said train of gears. Cooperating with the ratchet wheel 11 is an operating pawl 12 which causes the actuating mechanism to advance the registering dials or counters according to the distance traveled by the wheel. As here shown, this pawl is mounted on pin 13 which is slidably mounted in slot 14 in the supporting member 7 and is operated by the rotation of the hub relative to the supporting member to cause the pawl to actuate the registering mechanism. Mounted on the supporting member 7 near the center thereof is a stud 15 on which is mounted a detent pawl 16 which holds the ratchet wheel against reverse movement. This stud 15 also serves as a support for the face plate 17 which is secured to the stud by means of a screw 18.

The supporting plate 7 is so mounted that it is held against the rotation and the hub cap and its associated devices are permitted to rotate relative thereto. To this end there is shown a disc or plate 19 mounted in the hub cap at the inner end of the recess 4, this plate being preferably provided with a screw threaded flange 20 which is screwed into the opening forming the recess and thus is caused to rotate with the hub cap. This plate is provided with a central bearing 21 in which is journaled a stud or trunnion 22 carried by the supporting member 7 and which serves

50

90

to support that member and the registering mechanism in their proper positions in the recess 4. The trunnion 22 extends beyond the rear end of the bearing 21 and has secured thereto a plate 23 which constitutes one member of a thrust bearing and engages anti-friction balls 24 which are confined between the same and the front wall of an annular recess 25 in the plate 19. Rigidly secured to the bearing plate 23 is a bracket 26 having rearwardly extending arms 27 which are provided with slots 28 adapted to receive fingers 29 carried by a yieldable plate or spider 30 which is pressed rearwardly by means of a spring 31 confined between the same and the bearing plate 23. The yieldable plate 30 is provided with rearwardly extending lugs 32 which enter recesses 33 in the nut 3, thereby causing the spider, the bracket 26 and the supporting member 7 to be anchored to the spindle 2 and thus held against rotation. The plate 19 is provided with an eccentric boss 34 forming a part of bearing 21 and on this boss is mounted a yoke or eccentric strap 35 having an arm 36 in which the pin 13 is mounted. Pin 13 being held in slot 14 of the supporting member 7 will be held against rotation but will be free to slide in that slot and consequently the action of the eccentric 34 will impart reciprocatory movement to the pin and to the pawl carried thereby.

In order to prevent grease and oil from working their way through the bearing 21 about the trunnion 22 and thus entering the recess 4 and coming in contact with the registering dials, I have provided a special packing for the trunnion. As here shown, the rear portion of the bearing 21 is enlarged and is closed by an annular nut 37, between which and the forward portion of the bearing is formed an annular recess 38 adapted to receive a packing material of suitable character, shown at 39. Trunnion 22 is journaled at its front and rear portions in the bearing 21 and the nut 37, which in effect forms part of the bearing, and the trunnion is provided with a circumferential groove 40 which registers with the annular recess 38 of the bearing. When the packing nut 37 is tightened down it will exert pressure on the packing material 39 and a portion of this material will be forced into the groove in the trunnion. The pressure on the packing material will compress that portion thereof lying between the front and rear walls of the recess but that portion of the material which is forced into the groove will not be compressed to so great a degree and will retain its flexibility to such an extent that it will not become glazed or hardened by its contact with the trunnion, but will be at all times capable of absorbing any grease which may pass between the nut and the

trunnion, consequently the bearing is absolutely grease-proof.

The present registering device is designed primarily for use with five registering dials 9, but it is sometimes desirable to add a sixth dial to increase the capacity of the device. In order that this may be done, without rearranging or rebuilding the registering mechanism as a whole, I have provided a special supporting bracket which can be readily applied to or removed from the supporting member 7 and on which the additional dial may be mounted. This additional dial would necessarily be arranged beyond the left hand dial and would therefore lie in front of the actuating device or pawl 12, which is arranged between the stud 8 which carries the ratchet wheel 11 and the stud 8 which carries the left hand dial 9. As here shown, this bracket comprises the body portion 41 having an aperture 42 adapted to embrace the central stud 15. The bracket extends outwardly from the stud in a substantial radial direction, in front of pawl 12, and is provided at its outer end with an offset portion or arm 43 which preferably rests against the face of the supporting member 7 and extends laterally from the body portion 41 of the bracket and is provided with an aperture 44 to receive the stud 8 of the left hand dial 9. The body portion of the bracket is provided near its outer end with a stud 46 adapted to receive the additional dial, which is shown at 45, and its associated devices and to support this dial in front of pawl 12. It will be obvious that in assembling the registering device the bracket can be very quickly and easily placed in position therein and in this manner means is provided for supporting the additional dial without a change or rearrangement of the registering mechanism.

While I have shown and described one embodiment of my invention, I wish it to be understood that I do not desire to be limited to details thereof as various modifications may occur to a person skilled in the art.

Having now fully described my invention, what I claim as new, and desire to secure by Letters Patent is:

1. In a registering device comprising a supporting member, a stud arranged near the center of said member, a second stud carried by said member and spaced from the first mentioned stud and a registering element carried by the last mentioned stud, a bracket having an apertured portion engaging said central stud and extending substantially radially therefrom and also having a second apertured portion to engage said second stud, and means for mounting an additional registering element on said bracket at a point out of line with said studs.

2. In a registering device comprising a

supporting member, a stud arranged near the center of said member, a second stud carried by said member and spaced from the first mentioned stud and a registering element carried by the last mentioned stud, a bracket having an apertured portion engaging said central stud and extending substantially radially therefrom and also having a second apertured portion extending laterally from said radial portion to engage said second stud, a stud carried by said bracket, and an additional registering element mounted on the last mentioned stud.

3. In a registering device comprising a supporting member, a stud arranged near the center of said member, a second stud carried by said member and spaced from the first mentioned stud and a registering element carried by said second stud, a bracket having an apertured portion engaging said central stud and extending substantially radially therefrom, and having a second apertured portion offset from said radial portion and extending at an angle thereto to engage said second stud, a stud carried by the radial portion of said bracket, and an additional registering element mounted on the stud which is carried by said bracket.

4. In a registering device comprising two parts one of which is rotatable with relation to the other, studs carried by one of said parts, a registering element carried by one of said studs, and means controlled by the relative movement of said parts to actuate said registering element, a bracket having means for mounting the same on two of said studs, and an additional registering element mounted on said bracket in operative relation to the first mentioned registering element.

40 5. In a registering device comprising two parts one of which is rotatable with relation to the other, two studs carried by one of said parts and spaced one from the other, a registering element carried by one of said studs, and means controlled by the relative movement of said parts to actuate said registering element, a bracket having an apertured portion to engage one of said studs and having a laterally extending apertured portion to engage the other of said studs, a stud carried by said bracket, and an additional registering element mounted on the last mentioned stud and having means to operatively connect the same with said actuating means.

55 6. In a registering device comprising a supporting member, studs carried by said member, and a registering element mounted on one of said studs, separate means for providing said registering device with an additional registering element comprising a bracket having means for mounting the same on two of said studs, and means for mounting said additional registering device on said bracket in a predetermined position with relation to the first mentioned registering element.

7. In a registering device comprising a supporting member, studs carried by said member, and a registering element mounted on one of said studs, separate means for providing said registering device with an additional registering element comprising a bracket having apertured portions to engage two of said studs, a stud carried by said bracket and spaced from both of the studs which are engaged by said bracket, and a registering element carried by the last mentioned stud.

In testimony whereof, I affix my signature hereto.
